UNITED STATES PATENT OFFICE

108,859

DESIGN FOR A DRESS ENSEMBLE

Jacob Abbate, New York, N. Y.

Application January 21, 1938, Serial No. 74,454

Term of patent 3½ years

To all whom it may concern:

Be it known that I, Jacob Abbate, a citizen of the United States, residing at 50 Central Park South, in the county of New York, and city and State of New York, have invented a new, original, and ornamental Design for a Dress Ensemble, of which the following is a specification, reference being had to the accompanying drawing, constituting a part thereof.

Fig. 1 is a front view of the dress ensemble.

Fig. 2 is the rear view of the dress ensemble as shown in Fig. 1.

The dress blouse is conventional and comprises diagonal pleating and trimming.

The characteristic feature of my design resides in the specific design of the puffing on the jacket member of the ensemble, said puffing harmonizing with the trim on the dress front.

I claim:

The ornamental design for a dress ensemble substantially as shown and described.

JACOB ABBATE.
